CARD GAME

Paul J. Benrath, La Grange, Ill.

Application June 13, 1938, Serial No. 213,437

6 Claims. (Cl. 273—152)

This invention relates to a card game and more particularly to a card game that is educational as well as entertaining in character and involving the names and certain information regarding the thirty-one men who have served as presidents of the United States, and also involving the twelve months of the year and certain holidays.

Among the objects of this invention is to provide a card game that is educational as pointed out above and in other respects that will later more fully appear, as well as such game that will sharpen the wits and cultivate alertness, and at the same time afford the players with a maximum of pleasure and eliminate the undesirable features of dull moments and lack of interest.

Other objects, advantages and capabilities inherent in the invention will later more fully appear.

In the drawings:

Fig. 1 is a face view of twelve cards, shown partly overlapping for convenience, showing one on each card the twelve months of the year, and each card bearing certain information regarding the month indicated thereon.

Fig. 2 is a face view, in two rows, of thirty cards, shown, except for one card, partly overlapping for conservation of space, the thirty cards being numbered from 2 to 31 consecutively, the number on each card appearing large in the center and smaller in the two diagonally opposite corners.

Fig. 3 is a face view, in five rows, of thirty-one cards, those cards in the upper four rows being shown slightly overlapping for conservation of space, the three cards in the bottom row being shown separated for clarity, these thirty-one cards, respectively bearing the names of the thirty-one men who have served as presidents of the United States, together with certain information regarding each.

Fig. 4 is a face view of a card bearing the name of a day generally observed as a holiday, and certain information regarding the holiday named.

Fig. 5 is a face view of another card bearing the name of another day generally observed as a holiday, together with certain information regarding that holiday.

Referring more in detail to the drawings, it will be seen that this card game comprises preferably a total of seventy-five cards composed of five groups made up (1) of twelve cards, one for each month of the year as shown in Fig. 1, (2) of thirty cards numbered consecutively from 2 to 31 as shown in Fig. 2, (3) of thirty-one cards,

one for each of the thirty-one men who have served as presidents of the United States (Grover Cleveland being the twenty-second and twenty-fourth president) as shown in Fig. 3, (4) of one card representing Labor day or any other day generally observed as a holiday as seen in Fig. 4, and (5) one card representing Thanksgiving day or any other day desired which is generally observed as a holiday as shown in Fig. 5.

Describing each of these five groups in detail and referring first to those shown in Fig. 1, this group consists of twelve cards, one for each of the twelve months of the year, each having the name of the month printed thereon above the large numeral 1 in the center, and below said numeral 1 the designation as to which month numerically it is and the number of days in that month. For example, the January card, as seen in Fig. 1, has the large numeral 1 in the middle with the word "January" printed thereabove, and the designation "1st month" and "31 days" therebelow. Also the January card has in the upper left-hand corner and in the lower right-hand corner the numeral 1, so that said numeral will be quickly and plainly visible when a number of the cards are held in the hand of the player. February has similar information descriptive of that month, to-wit, the word "February" above the large numeral 1 in the center of the card, and the designation below the numeral 1 that February is the 2nd month and has 28 days. Also below this is the further information that in Leap Year February has 29 days. The numeral 2 is added to the top center of the February card because of February being the second month, and in each of the upper left-hand corner and lower right-hand corner are the numerals 1 and 2, the 1 designating that this is one of the month group and the 2 designating February the second month of the year. May has the enlarged numeral 1 in the center with the word "May" thereabove, and the designation therebelow that it is the 5th month with 31 days. In the upper left-hand corner is the numeral 1 designating that this is a card from group 1 (meaning the month group), and a 5 below the 1 designating that May is the fifth month. Also in the lower right-hand corner is a similar arrangement of numbers except that they are upside down (as in the other cards) relative to those in the upper left-hand corner, so that they will be visible to the player regardless of whether the card is held in the hand right side up or upside down. Also in the middle of the top of the May card when held right side up is the numeral 5 because of May being the fifth

month. Each of the twelve month cards is correspondingly arranged with an enlarged numeral 1 in the center, the name of the month immediately thereabove, and the number of the month as well as the number of days immediately below said enlarged number, with the number of the month also in the middle of the upper edge of the card and the numeral 1 immediately above a number representing the number of the month in the year in the upper left-hand corner, and numbers in the lower right-hand corner similar to those in the upper left-hand corner except for being upside down for reasons pointed out above. This order and arrangement of names and numbers on the month cards will be readily understood from an inspection of Fig. 1.

The enlarged number in the center of each of the month cards as well as each of the numerals 1 in each of the upper left-hand corner and lower right-hand corner, will preferably be in red because of being numbers that count against the player if held in his hand at the end of the game, as will be explained more fully later in describing how the game is played. Also as described more fully later herein, in addition to the numeral 1 because of being red counting against the player if held in his hand at the end of the game, these numerals 1 also indicate that one of the month cards is to be the first card played at the beginning of the game.

Referring now to Fig. 2, it will be seen that this group of cards comprises thirty cards each bearing in its center an enlarged number, these numbers appearing one on each card consecutively from 2 to 31. Also each of these cards bears a number in each of the upper left-hand and lower right-hand corners corresponding to the number in the center of the card, but smaller and positioned so that whichever corner number is at the top it will be read in proper position to enable a quick reading of these numbers regardless of whether the cards be held in the hand upside down or not. Each of the three numbers on each of these cards being described will preferably be printed in red to indicate that such of these numbers as are held in the hand of the player at the end of the game count against such player, as will be later more fully described. While all except the first card, bearing the number 2, are shown in Fig. 2 as being overlapped one over the other, the only upper faces being completely visible being cards 2, 16 and 31, it is to be understood that each of the other cards are correspondingly printed as described above, to-wit, the number in the center of the cards will increase consecutively and each card will have in its upper left-hand corner and reversed in position in the lower right-hand corner, a number corresponding to the enlarged number in the center. For example, card 10 will have a 10 in the upper left-hand corner, an enlarged 10 in the center and a 10 upside down in the lower right-hand corner, the card 21 will have a 21 in the upper left-hand corner, an enlarged 21 in the center and a 21 upside down in the lower right-hand corner, and so on for each of the cards.

Referring now to Fig. 3, this group comprises thirty-one cards numbered with an enlarged number in the center, increasing progressively from 1 to 31, these cards, as explained above, representing the thirty-one men who have served as presidents of the United States, their names appearing immediately above the enlarged number in the center, the center number also having

the word President printed across its face. Also in this group, as in the preceding groups, the enlarged number in the center is printed in red as well as the corresponding number in the upper 5 left-hand corner and lower right-hand corner, this red color indicating that such numbers (or the sum of such numbers if more than one is held) if held in the hand of the player at the end of the game count against that player as explained later.

Also each of the cards in this president group in addition to the consecutive numbers referred to above in the center of the card, carry just above such number the name of the man who 15 was president of the United States in that consecutive order, and below such number the date of his birth and the date of his death. Also in the upper left-hand corner (in reverse position in the lower right-hand corner) immediately below the number corresponding to the number in the center of the card is a number corresponding to the day of the month that that president was born, and immediately below this a number corresponding to the day of the month that that 20 president died. Also in the middle of the top of each of these president cards is a number corresponding to the day of the month that that particular president was born, and in the upper right-hand corner is a number corresponding to the day of the month that that particular 25 president died. For example, on the president card having the enlarged red numeral 1 in the center, the name "George Washington" appears directly thereabove, while directly below this central number appears in two lines the information "born Feb. 22, 1732" and "died Dec. 14, 1799", thus showing the date on which George Washington, the first president, was born, and the date he died. In the upper left-hand corner of this 30 card appear in sequence vertically the numerals 1, 22 and 14, the 1 indicating that he was the first president, the 22 indicating that he was born on the 22nd day of the month, and the 14 indicating that he died on the 14th day of the month. Also the 22 in the central portion of the 35 top of the card indicates that he was born on the 22nd day of the month, and the 14 in the upper right-hand corner indicates that he died on the 14th day of the month. As stated above, numbers corresponding to those in the upper left-hand corner of the card are also placed in the lower right-hand corner but upside down so that these numbers may be read either way the 40 card is held in the hand of the player. The same significance attaches to each of the other 45 cards for the particular president named thereon, for example, card 16 shows that Abraham Lincoln was the sixteenth man to serve as president of the United States, that he was born February 12, 1809, that he died April 15, 1865, and this card has the numbers 16, 12 and 15 in vertical position in the upper left-hand corner to show that he was the sixteenth man to serve as president, that he was born on the 12th day of the month and that he died on the 15th day of the month, these same three numbers appearing 50 in the lower right-hand corner but in upside down relation to those in the upper left-hand corner for reasons stated. Also the numeral 12 in the middle of the top of this card shows that he was born on the 12th day of the month, and the 15 in the upper right-hand corner indicates that he died on the 15th day of the month.

The card shown in Fig. 4 bears the name "Labor day" and the information thereunder

that Labor day is the first Monday in September.

The card shown in Fig. 5 bears the name of the holiday "Thanksgiving day" and the information thereunder that Thanksgiving day is the last Thursday in November. It will, of course, be understood that instead of these two particular holidays, any other outstanding days may be selected for these cards with the corresponding information without departing from the spirit of my invention.

The color scheme on the cards is red, white and blue, the penalty numbers being red, the other numbers and letters being blue, and the background of the face of each card being white. Other colors may be used if desired.

Having described the details of the various cards in the various groups, the manner of playing this game will now be described.

To play the game the dealer deals out nine cards each for two to five players, seven cards each for five to eight players and five cards each for more than eight players. The dealer then turns the deck face down on the table and the player next to the left of the dealer first draws one card from the top of the deck and then in order to be able to make a play on the board the player must have one of the twelve month cards to start the game, or if he does not have one of the twelve month cards he must discard a card face up alongside of the deck. If the player has one of the twelve month cards he can make only one play by laying this or any other month card that he might happen to have face up on the table and then discard one card face up as stated alongside of the deck. Then the next player to the left draws a card either from the top of the deck or the top of the discard pile as he chooses, and then makes his play on the table if able. In order to make a play on the table the player must have either one of the other month cards falling within the same quarter of the year that the first month card played falls or a card having along its top edge a number next consecutively larger than the red 1 at the upper left-hand corner of the month card first played. In other words, in order to be able to play the player must have a card in his hand which has anywhere along the top row of numbers on the card a 2, which 2 can be either red or blue, or a month card in the same quarter as the month card already played. When playing a second or third month card it must be placed laterally separate from the month card already played so as to start another column. After making one play on the board the player then discards any card he chooses face up on top of the discard pile.

The next player to the left likewise first draws a card from the top of the deck or discard pile and then may play either one of the other two month cards in the same quarter or a card having along its upper edge a number next successively higher than the number on the card last played in alignment with the red numeral 1 in the upper left-hand corner of the first card. In other words, a 3, or a month card in the same quarter. After making this play the player then discards one card face up on the top of the discard pile, and the next player to the left proceeds in the same manner until one of the players is out of cards, in which case he is the winner and the others are respectively beaten by the total of the red numbers on the cards still remaining in their hand. The total number of cards played in any aligned row must equal the number of

days in the month of the month card first played. For example, if the first month card played is July, which shows on its face to have 31 days, there must be thirty-one cards in this aligned column, and the numbers in alignment must run consecutively from the 1 in the upper left-hand corner of the card first played to 31 on the last card played. As stated, except for its being compulsory to build up on the 1 in the upper left-hand corner of the first card played, any number can be used appearing in the top row of the respective cards played, providing that such number be the next consecutively larger number with relation to the card on which it is laid, and the numbers must be in alignment, as stated, with the 1 in the upper left-hand corner of the first card played.

As is well known, the four quarters of a year constitute January, February and March for the first quarter, April, May and June for the second quarter, July, August and September for the third quarter and October, November and December for the fourth quarter. When the game is started by the first player playing a month card on the board or table, this limits the rest of the game to the three months in that quarter within which the first card played falls, so that if, for example, January is the first card played, each player in turn must either build up starting with the 1 in the upper left-hand corner of the first card played with the numbers consecutively, or play a card representing one of the other two months in the same quarter, for example, either February or March. If May is the first card played (it being kept in mind that the first play is always limited to one of the twelve month cards), then the players in their proper order to the left must either play a successive numerical build-up card in the manner stated above or play one of the other two cards constituting the other two months of that particular quarter. Assuming May to be the first month card played, the only other month cards that can be laid on the table during a player's turn is either April or June, which are then open to be built upon with successive numbers in alignment with the 1 in the upper left-hand corner of the month card as stated above.

If September is the first month card played, the numbers will be successively built up to 30 as September has thirty days as stated on the face of the September card. If August is the first month card played, the numbers will be successively built up in alignment with the 1 in the upper left-hand corner of the first card to 31, as August has thirty-one days as stated on the face of this card, and so on, keeping in mind that if February is the first card played, in Leap Year the successive numbers will be built up to 29 and otherwise to 28. In building up the numbers successively from the 1 in the upper left-hand corner of the first card played, any number along the upper edge of any of the cards except the three month cards of the particular quarter involved may be used for the successive building up operation. In other words, any one of the numbers along the upper edge of any one of the other month cards outside of that quarter may be used, as well as any one of the numbers at or along the upper edge of any of the other cards, including the number cards or the president cards, may be used in the building up operation, but it should be kept in mind that the building up must occur in alignment with the 1 in the upper left-hand corner of the

first card played and the numbers be laid on the board in sequence.

If the player about to play sees that he can make a play with the top face up card of the discard pile, he is at liberty to draw that card instead of the top card from the up-turned deck if he chooses, but each player must draw a card from one or the other of these two places before playing. After making a play he must then discard one card face up upon the discard pile. To put it another way, each player first draws one card, next makes a play if able, and third discards a card face up on the discard pile. In discarding he can, of course, discard any card from his hand which he chooses.

In playing the month cards outside of the quarter being played, the numbers at the top of the card can be used the same as the numbers at the top of any of the other cards in building up the numerical sequence. For example, if the first card played is February, the other two months of that quarter being January and March, April, which is the fourth month, can be used as a 4 after the 3 card has been played, placing the 4 under the 3 in alignment therewith.

The two holiday cards, to-wit, Labor day and Thanksgiving day are good for any play that the player chooses. In other words, the player can call either of these two holiday cards any number he chooses at any time he chooses and use them in any play he chooses, except he cannot play either of them as the first card played or as the first card in starting a new column. As these two holiday cards do not count for any points, since they do not have any red numbers thereon, it would be to the player's advantage to save these cards as long as possible in the hope that when holding that card only in his hand he could go out and thus be the winner.

If a player has a play on the board and does not make it but discards the card that he could have played, any player who first calls the player's attention to his mistake is entitled to give the player making the mistake one of the cards from his hand. This, however, applies only when the player discards without making a play. If he first makes a play and then discards a card that could be played, this is not called a mistake.

When the deck is all out and no one has won, the game can either be terminated at that time and the one having the smallest total of red numbers on the cards still in his hand wins, the degree of defeat of the others being determined by their total of red numbers, the greater the total the greater the defeat. If it is desired to continue the game the discard pile can be turned over without shuffling and the game continue either as long as desired or until one of the players goes out.

While I have shown particular groups of specific cards in the deck of my new game, I wish it understood that the groups or any of them or any of the cards in any of the groups may be varied by omitting some or adding others, and that the particular group or specific information on the cards and arrangement of the same are susceptible of modification and change without departing from the spirit of my invention. The holiday cards may be changed in name or character, omitted entirely, or increased in number, which is also true of each of the other groups.

Having now described my invention,

I claim:

1. In a card game of the character described, a pack of cards comprising three groups based

on the months of the year, the number of days in a month, and the presidents of the United States, the cards of each group bearing numerals the highest of which equals the number of days in the longest month in the year, each of the cards in the month group bearing the numeral "1", the cards in the president group bearing numerals in sequence from "1" to "31", and the cards in the remaining group bearing numerals in sequence from "2" to "31", the cards in the three groups being capable of being built up in sequence from "1" to a numeral equal to the number of days in the month of the month card first played.

15 2. In a card game a pack of cards having three groups of cards, comprising a month group, a presidential group and a numeral group, the month group having a card for each month of the year, each card bearing in its central portion a numeral "1" in red color and on each of its upper left-hand and lower right-hand corners the same numeral in red color, the presidential group having a card for each of the thirty-one men who has served as president of the United States, each of these cards having the name of one of said men thereon with a red number in the center corresponding to the numerical order of the serving of that man as president with a corresponding red numeral on each of its upper left-hand and lower right-hand corners and other different colored numerals on a plurality of edges within the range of 1 to 31, the numeral group bearing one to a card in sequence in red color central numerals from 2 to 31, and a red numeral on two of the edges of each card corresponding to the central numeral, there being no numeral on any of the cards of the three groups exceeding a numeral equal to the number of days in the longest month of the year, whereby groups

40 may be formed with a month card first and other cards from any of the three groups following in sequence from "2" to a number corresponding to the number of days in the month of that particular month card.

45 3. In a card game a pack of cards having two groups of cards comprising a month group and a presidential group, the month group having a card for each month of the year and each card thereof bearing in its central portion a numeral "1" in red color and on two of its marginal edges also in red the same numeral and a different colored numeral corresponding to the numerical order of the month, the presidential group having a card for each of the thirty-one men who has served as president of the United States, with his name thereon together with a major numeral in red color representing the numerical order of the serving of that man, the same numeral also appearing in red color on two of the marginal edges of the same card, there also appearing in other color than red along at least one edge of each of the presidential cards numbers corresponding to the day of the month of that president's birth and the day of the month of his death, whereby groups may be formed starting with a month card and continuing in sequence with marginal numerals on other cards up to the number of days in the month of the first card.

50 4. A card game having a pack of cards comprising three groups of cards, one group consisting of one card each for all of the months of the year, each of these cards having a numeral "1" and also a numeral corresponding to the numerical order of the month in the year, another group having one on each card the names of the thirty-

one men who have served as president of the United States, and also numerals representing the numerical order of that man as president and the day of the month of his birth and the day of the month of his death, and the third group bearing numbers from "2" to "31," whereby groups may be formed with a month card at the beginning and other cards with their numerals progressing in sequence from the numeral "1" to a number corresponding to the number of days in the month of the beginning card.

5. A card game having a pack of cards comprising a card for each month of the year each bearing the name of its respective month, a numeral representing the numerical order of the month in the year, the number of days in that month and the numeral 1, and a group of thirty-one president cards bearing respectively the names of the thirty-one men who have served as president of the United States, together with a numeral representing the numerical order of the serving of that man, and a numeral corresponding to the day of the month of his birth and a numeral corresponding to the day of the month of his death, and a group of numeral cards bearing numerals running in sequence from "2" to "31," whereby groups may be formed beginning with a month card and the number of days in that month built up in sequence from the other cards.

6. In a card game a pack of cards having three groups of cards comprising a month group, a presidential group and a numeral group, the month group having a card for each month of the year and each bearing in its central portion a numeral "1" in red color and the name of the month, the numerical value of the month and the number of days in that particular month, each of said month cards having in its upper left-hand corner in red color the numeral "1" and immediately therebelow a numeral representing the numerical value of the month in some other color than red, and also near the middle of the upper edge of said card a number representing the numerical value of that month in some other color than red, the presidential group having a card for each of the thirty-one men who have served

as president of the United States, each of these presidential cards having the name of one of said men thereon with a red number in the center corresponding to the numerical order of the serving of that man as president with a corresponding red numeral on its upper left-hand corner, and each of said presidential cards also having in its central portion in other color than red the date of birth and the date of death of that respective president, each of the presidential cards also having in its upper left-hand corner numerals in other color than red and in vertical alignment corresponding to the days of the month and death of that respective president, and a numeral in the middle of the upper edge portion in other color than red corresponding to the day of birth of that president, and a numeral in color other than red in the upper right-hand corner corresponding to the day of death of that president, the numeral group of cards bearing one to a card in sequence in red letter central numerals from "2" to "31" and a red numeral in the upper left-hand corner corresponding to the central numeral, there being no numeral on any of the cards of the three groups exceeding a numeral equal to the number of days in the longest month of the year whereby after the cards are dealt a player will first play a month card and the following players after the first play will each in turn lay on the board a card having the next higher number over the preceding card, any month card in the same quarter as that of the first card played on the board to one side of the first month card played, and thereafter the players in turn laying on the board a card having the next higher number over the preceding card until one of the players goes out and becomes winner, the only month cards playable to start a new column in the manner set forth above being month cards from the same quarter as that of the first month card played, each column terminating with a number corresponding to the number of days in the month of the first card played in that particular column.
